UNITED STATES PATENT OFFICE.

ANDREW JACKSON COCKERELL, OF CHILlicothe, OHIO.

FROST-WATER SHIELD FOR GAS-METERS.

987,111.

Specification of Letters Patent. Patented Mar. 21, 1911.

Application filed May 2, 1910. Serial No. 558,993.

To all whom it may concern:

Be it known that I, ANDREW J. COCKERELL, a citizen of the United States, residing at Chillicothe, in the county of Ross and State 5 of Ohio, have invented a certain new and useful Frost-Water Shield for Gas-Meters, of which the following is a specification.

Gas meters are equipped with registers for 10 registering or recording the volume of gas passing through the measuring chamber of the meter, and in certain types of gas meters, more particularly the so-called dry meter, the register is mounted upon the bowl of the meter and operated by a shaft extending 15 through a stuffing-box in the top of the bowl. In meters of this type, of which the Tobey dry meter is one I have especially in mind, the mechanism sometimes becomes disordered by reason of the fact that during the 20 winter season, when there is freezing and thawing weather, water accumulating from the sweat on the glass face or dial of the register collects in the stuffing box and freezes thereby disconnecting or breaking 25 the gear connections and stopping the registration of gas, with consequent loss of revenue to the gas company.

It is the object of my invention to obviate 30 the above mentioned difficulty by discharging any accumulated moisture in the register box to the exterior of the meter; and this object I attain by means substantially as illustrated in the accompanying drawings, in which:

35 Figure 1 is a central vertical elevation partly in section of a Tobey gas meter having my improvement embodied therein. Fig. 2 is a plan view of the water shield which is interposed between the register mechanism and the stuffing box.

The nature of the operating or measuring mechanism of the meter selected for illustrating my invention, will be understood by reference to the U. S. patent to Tobey, No. 45 487,907, dated December 13th, 1892, so that a specific description of the same herein will be unnecessary.

In the drawings, 1 denotes the globular case or bowl of the meter, containing the 50 measuring mechanism which is actuated by the flow of gas through the meter and operates a crank-shaft 2 which passes through a stuffing-box 3 or packing gland contained in a socket in the top of the bowl. Mounted upon the top of the bowl, over the stuffing-box 3, is the register box 4, which contains

the registering mechanism and has a glass face plate over the dial. The register-box has an open bottom and is fastened upon the bowl by screws 5 inserted through lugs projecting from the base of the register-box. Operative-connection between the register-mechanism and crank-shaft 2 is provided by a crank-arm 6 on said shaft which engages an arm 7 on the shaft 8 of pinion 9, 65 which latter communicates motion to the gearing of the register. An arm 10 affixed inside the register-box provides a bearing 11 for the shaft 8.

As thus far described the structure is not 70 novel, and it has been found in practice that the accumulation of moisture from the sweat on the face of the dial collects in the stuffing-box and freezes with the objectionable results before stated. To obviate this trouble, I have provided a frost water shield 12, consisting of a convex plate, preferably of sheet metal, which is placed upon the top of the bowl over the stuffing box and under the register-box, the same being clamped between the register-box and the bowl. The 75 said shield or plate has a central opening 13 for the passage of the crank-shaft 2, and has diametrically opposite marginal projections or tabs 14 and, preferably, intermediate marginal projections or tabs 15. The 80 projections 14, which are arranged under the lugs at the foot of the register-box, are apertured and receive the same screws 5 which fasten the register-box on the bowl. 85 The other two projections 15 are simply rests for the shield, and fit between the bottom of the register-box and the top of the bowl. These projections or tabs raise the 90 bottom of the register-box slightly above the top of the bowl, and leave an opening around the rim or margin of the shield for the escape of water from the upper surface of the shield.

With this device, water collecting from 100 the glass face or dial of the register-box falls upon and is shed by the convex upper surface of the shield, and is discharged under the bottom edges of the register box upon the outside of the meter case or bowl; 105 thus preventing derangement of the mechanism of the meter from the cause hereinbefore mentioned.

The water shield will of course, protect 110 the stuffing box from sweat collected from the entire register box. The shield will also protect the mechanism from broken glass,

it being frequently found that the dial is broken and particles of glass get into the mechanism, thereby interfering with its operation; and the shield will in fact protect the stuffing box from any and all foreign substances.

I claim as my invention and desire to secure by Letters Patent:

1. In a gas meter having a register-operating shaft extending through a stuffing-box in the top of the bowl of the meter, and having a register-box mounted upon the bowl over the stuffing-box, the combination with the bowl, shaft, stuffing-box and register-box, of a shield for the stuffing-box arranged in the lower part of the register-box and having an outwardly-sloping upper surface for shedding water accumulating from the sweat on the glass face or dial of the register, the apparatus being constructed to provide an opening under the bottom edge of the register-box for escape of water from the shield to the exterior surface of the bowl.

2. In a gas meter having a register-operating shaft extending through a stuffing-box in the top of the bowl of the meter, and having a register-box mounted upon the bowl over the stuffing-box, the combination with the bowl, shaft, stuffing-box and register-box, of a plate arranged over the stuffing-box and having a central opening for said shaft and having a convex or sloping upper water-shedding surface, said plate having marginal projections or tabs clamped between the bottom of the register-box and top of the bowl, thereby slightly elevating the bottom edge of the register-box and leaving a space between the latter and the edge of the plate for the discharge of water to the exterior surface of the bowl.

In testimony whereof I affix my signature, in presence of two witnesses.

ANDREW JACKSON COCKERELL.
